EXCELSIOR

Des. 1173

Thomas Lincoln & Samuel Lincoln,
of Providence Rhode Island,
Letters Patent No. 1473, dated Dec. 20, 1857.

The Schedule referred to in these Letters Patent and making part of the same.

To all whom it may concern:

Be it known that we Thomas Lincoln and Samuel Lincoln,
of the City and County of Providence, in the State of Rhode Island, have produced a
new and original design for a label to be employed to distinguish a new composi-
tion of Soap, and we do hereby declare that the following, taken in connection with
one of the labels making a part of the same is a full and exact description thereof.

The ornamental border as shown, surrounding a colored ground
in which are the words in colors contrasting with the ground.

S. R. Jackson & Co

Windsor

Chemical Erasive Soap.

The right and left, upper corners being filled with a scroll as

shown: a star with rays directly over the center of the word "Windsor", and a leaf on either
hand of this word & below it in the spaces caused by the curvature in opposite directions of
the lines "Windsor" and "Chemical Erasive Soap", the whole being surmounted by the
word "Excelsior".

I claim the new design for a label for boxes of Soap consisting of
the words and ornamental devices as above described and represented in the drawing.
